UNITED STATES PATENT OFFICE

DELBERT L. HIBBERD, OF LODGE POLE, NEBRASKA

DESIGN FOR A CASING FOR A POCKET PROPHYLACTIC UNIT

Application filed October 10, 1929. Serial No. 32,990. Term of patent 7 years.

To all whom it may concern:

Be it known that I, DELBERT L. HIBBERD, a citizen of the United States, residing at Lodge Pole, in the county of Cheyenne and State of Nebraska, have invented a new, original, and ornamental Design for a Casing for Pocket Prophylactic Units, of which the following is a specification, reference being had to the accompanying drawing, forming part thereof.

Fig. 1 is a side view of a casing for a pocket prophylactic unit, showing my new design, Fig. 2 is an end view of the same, and Fig. 3 is a transverse section on the line 3—3 of Fig. 1.

I claim:

The ornamental design for a casing for a pocket prophylactic unit, as shown.

DELBERT L. HIBBERD.
